UNITED STATES PATENT OFFICE.

JAMES A. EDEN, JR., OF SPRINGFIELD, MASSACHUSETTS, ASSIGNOR TO BAUSH
MACHINE TOOL COMPANY, A CORPORATION OF MASSACHUSETTS.

BLANK-FEEDING MECHANISM FOR METAL-WORKING MACHINES.

1,159,195.

Specification of Letters Patent.

Patented Nov. 2, 1915.

Application filed May 15, 1914. Serial No. 838,677.

To all whom it may concern:

Be it known that I, JAMES A. EDEN, Jr., a citizen of the United States, residing in Springfield, Massachusetts, have invented 5 certain new and useful Improvements in Blank-Feeding Mechanisms for Metal-Working Machines, of which the following is a specification.

This invention has for its object to provide an improved mechanism for selecting 10 a single article or blank from a large number contained in a suitable receptacle, and delivering the articles one at a time at a certain part of the device.

15 A further object of the invention is to provide in connection with such an arrangement, a member operating in timed relation to the delivery of each article or blank, whereby the position of the blank will be 20 changed from that it occupies as delivered by the selecting member.

In the accompanying drawings showing 25 one embodiment of my invention, Figure 1 is a side elevation of the device; Fig. 2 is a vertical section on the line 2—2 of Fig. 1; Fig. 3 is a plan view of the device; Fig. 4 is a fragmentary side view at the upper part of the device; Fig. 5 is a similar view with the parts in shifted positions; Fig. 6 is a vertical section on the line 6—6, indicated on Fig. 4; Fig. 7 shows separately the stop piece on the arm that selects and delivers the blank.

Referring to the embodiment of the invention illustrated, a suitable base 8 carries 35 an upright frame 9, which supports a frame 10 for vertical adjustment by means of threaded rods 1 on each side; and the frame 10 carries a hopper 11 into which the blanks 40 or articles *b* are placed in large quantities.

The hopper has one or more bottom walls inclined, and a reciprocating slide is provided which when lowered will have its upper edge adjacent to the bottom of the 45 inclined wall so as to have one of the blanks fall by gravity on such upper edge. When the slide is elevated, it will carry the selected blank upward above the other blanks in the hopper and will deliver it to the machine.

50 The upper portion of the slide comprises a movable member or arm which is suitably shaped to select and convey upward the single blank and which is adapted to be tilted to cause the selected blank to be delivered or slide off by gravity.

In the construction set forth, the hopper 11 is shown as having a pair of downwardly converging walls whose lower edge portions 14 and 15 are spaced apart to permit the vertical reciprocation of a slide 16 which is 60 operated from a yoke 17 connected by a link 18 with an arm 19 which is adjustably pivoted in a slotted bracket 20, as indicated in Fig. 2. This arm 19 has a slot 21 into which extends a crank pin 22, carried by a disk 23, 65 that is rotated by a shaft 24; by which means the slide 16 is vertically reciprocated. These operating parts are so proportioned that at its lowest position of movement the slide 16 will be in the position indicated in 70 Fig. 6.

The upper edge of the slide 16 comprises a grooved arm 25 hinged to the body of the slide at the point 26; the arm in its normal position resting horizontally on the body of 75 the slide, as indicated in Figs. 4 and 6, and having a portion 27 extending beyond the hinge 26 a short distance, but not enough to overbalance the main portion of the arm. Thus the arm will normally lie in the horizontal position.

When the slide is in the position indicated in Fig. 6, the arm 25 will have its grooved upper edge at the lower edges of the inclined walls of the hopper so that one of the blanks 85 *b*, shown in the form of rods suitable for the manufacture of bolts, will fall into the groove in the top of the arm 25; whereby when the slide is elevated by the described means, the selected blank *b*' will be carried upward. The 90 groove in the top of the arm 25 is so shallow (see Fig. 6) that the blank resting therein projects upward sufficiently to force aside other blanks as it rises through them and thus to exclude such other blanks from the 95 groove. By reason of this selection of a single blank and exclusion of others from the groove the lifting of the blank and the sliding of it off the arm 25 are perfectly simple operations and can be executed at a 100 comparatively high rate of speed.

As the slide reaches its uppermost position, the arm is automatically tilted to an inclined position as indicated in Figs. 1 and 5, whereby the blank *b*' will slide down the 105 groove in the arm by gravity, and thus be delivered or ejected from the device; the arm 25 being shown as provided with a stop pin 30 that as the arm approaches its uppermost position will strike a lug 31 on 110

the frame member 10, and cause the arm to be tilted to the position indicated in these views, to eject the blank; the arm 25 returning to normal horizontal position as the 5 slide is lowered.

The final delivery of the blank from the arm 25 may be regulated to take place at the final portion of the upward movement of the slide by providing a stop piece at the 10 extremity of the extension 27 of the arm; a stop piece 32 being shown pivoted on the side of the part 27, and having a bent end 33 that normally extends across the end of the groove, being normally retained in this 15 position by gravity, also assisted by a spring 34.

When the arm 25 is shifted by the stop lug 31 at the latter portion of the upward movement of the slide, the stop piece 32 will 20 strike a strip 35 fast on an arm 36 extending out from the frame 10, whereby this stop piece 32 will have its end 33 swung down beyond the groove in the arm to release the blank and permit it to slide from the arm. Fig. 25 1 shows the arm swung only far enough to bring the stop piece 32 into engagement with the strip 35, the blank b' being still held in the arm. Fig. 5 shows the swinging movement of the arm completed and the 30 stop piece withdrawn from over the end of the arm.

While this device is designed to feed blanks of various kinds to various kinds of machines and mechanisms, it is particularly 35 adapted to feed bolt blanks to a rotatable head member provided with a circular series of holders, each comprising a pair of gripping members; and in Fig. 1 a portion of a head of this character is shown at 40, 40 having a lower gripping member 41, that is so arranged relatively to the feeding device that it will receive the lower end of the blank b' as it slides down the arm 25. In order to bring the upper end of the blank 45 b' into a coöperating gripping member 42 I provide a lever 43 pivoted at 44 on the arm 36, the said lever having a wide end portion 45 arranged in the path of movement of the blank b' as it falls from the 50 tilted arm, the end portion 45 swinging upward at the proper time to swing the blank inward to the desired upright position. This lever 43 has an extension 46 that may be weighted at 47, and the extension rests 55 on a pin 48 on the slide 16, whereby as the slide moves up and down the lever will be swung. In the uppermost position of the slide the lever extension will be raised and the end portion 45 will be moved away from 60 the head; and when the slide is lowered the arm 46 will move downward and the end portion 45 will be shifted toward the head, so as to swing the blank (that now has its lower end in the gripping member 41) inward to a vertical position.

Though I have described with great particularity of detail a certain specific embodiment of my invention yet it is not to be understood therefrom that the invention is restricted to the particular embodiment disclosed.

Various modifications thereof in detail and in the arrangement of the parts may be made by those skilled in the art without departing from the invention, as set forth in the appended claims.

What I claim is—

1. An apparatus for feeding rod-shaped blanks comprising a hopper adapted to carry a number of such blanks in parallel substantially horizontal positions, a member having a narrow upper edge with a groove so as to accommodate one of said blanks in a position parallel to those in the hopper, and means for lifting said member through said blanks to an inclined position elevated above the blanks in the hopper, so as to select and elevate a single blank in said groove and to cause the selected blank to slide in endwise direction off said member, said groove being so shallow that a blank resting on the bottom of said groove projects upward sufficiently to exclude other blanks from the groove in rising through them.

2. An apparatus for feeding rod-shaped blanks comprising a hopper adapted to carry a number of such blanks in parallel positions, a member having a narrow upper edge with a shallow groove so as to accommodate only a single one of said blanks in a position parallel to those in the hopper, and means for lifting said member through said blanks to an inclined position elevated above the blanks in the hopper, so as to select and elevate a single blank in said groove and to cause the selected blank to slide in endwise direction off said member, said hopper having an inclined wall with a substantially horizontal lower edge engaging said member, so that the reciprocation of said member through the blanks supported on said wall tends to cause said blanks to assume parallel horizontal positions.

3. An apparatus for feeding rod-shaped blanks comprising a hopper adapted to carry a number of such blanks in parallel substantially horizontal positions, a member having a narrow upper edge with a groove so as to accommodate one of said blanks in a position parallel to those in the hopper, and means for lifting said member through said blanks to an inclined position elevated above the blanks in the hopper, so as to select and elevate a single blank in said groove and to cause the selected blank to slide in endwise direction off said member, said groove being so shallow that a blank resting on the bottom of said groove projects upward sufficiently to exclude other blanks from the groove in rising through them, a

- stop adapted to prevent the escape of a blank from the discharge end of said groove and to be withdrawn to permit such escape automatically at a determined time.
- 5 4. An apparatus for feeding rod-shaped blanks comprising a hopper adapted to carry a number of such blanks in parallel positions, a member having a narrow upper edge with a shallow groove so as to accommodate only a single one of said blanks in a position parallel to those in the hopper, and means for lifting said member through said blanks to an inclined position elevated above the blanks in the hopper, so as to select and elevate 10 a single blank in said groove and to cause the selected blank to slide in endwise direction off said member, in combination with a work holder into which the blank is received in an inclined position from said member, and means for swinging said blank into an upright position in said holder.
- 15 5. A blank feeding apparatus adapted to coöperate with a work holder for receiving such blanks, said blank feeding apparatus comprising a positioning member located adjacent to said holder, means for feeding a blank to an inclined position resting against said positioning member and supported at its lower end in said work holder and means 20 for moving said positioning member toward the holder to force the blank completely into the holder.
- 25 6. An apparatus for feeding rod-shaped blanks comprising a hopper adapted to carry a number of such blanks in parallel positions, a member having a narrow upper edge with a shallow groove so as to accommodate only a single one of said blanks in a position parallel to those in the hopper, means 30 for lifting said member through and above said blanks, said member being pivotally mounted and a stop for limiting the upward movement of the outer end of said member, so that said member selects and elevates a 35 single blank in said groove and is then tilted to cause the selected blank to slide in endwise direction off said member.
- 40 7. A blank feeding apparatus comprising a hopper having at its bottom a downwardly inclined wall, a slide vertically movable at the lower edge of said wall, an arm pivoted at the upper portion of the slide to normally rest on the top edge of the slide, the arm having its upper edge grooved to 45 receive a blank therein from the hopper when the slide is lowered to bring the arm to the bottom of the hopper adjacent said inclined wall, means for automatically tilting the arm when the slide is elevated above the hopper whereby the blank in the groove of the arm will slide down the same by gravity, a stop on the slide for swinging said lever from the movement of said slide.
- 50 In witness whereof, I have hereunto signed my name in the presence of two subscribing witnesses.
